UNITED STATES PATENT OFFICE.

JOHN SCHADE, OF HOLYOKE, MASSACHUSETTS, ASSIGNOR TO NATIONAL BLANK BOOK COMPANY, OF HOLYOKE, MASSACHUSETTS, A VOLUNTARY TRUST ASSOCIATION.

LOOSE-LEAF METAL LEDGER BACK.

Application filed August 30, 1921. Serial No. 436,906.

To all whom it may concern:

Be it known that I, JOHN SCHADE, a citizen of the United States, residing at the city of Holyoke, in the county of Hampden and State of Massachusetts, have invented 5 certain new and useful Improvements in Loose-Leaf Metal Ledger Backs; and I do declare the following to be a full, clear, and exact description of the invention, such as will enable others skilled in the art to which it appertains to make and use the same.

This invention relates to certain new and useful improvements in loose leaf metal ledger backs, and the primary object thereof 15 is to provide novel and improved means for latching the two telescopic sections, comprising the back, into assembled form.

A further object of the invention is to provide latching means which is of simple 20 form, capable of economical production, and having a minimum of moving parts subject to derangement.

The invention further aims to provide a simple telescopic means for connecting the 25 sections at the ends thereof and a latching structure disposed centrally between the ends so as to act equally upon each of the ends in holding the sections together.

Further and other objects will be later 30 set forth and manifested in the course of the following description.

In the drawings:

Figure 1, is a top plan view of the structure in assembled form;

Figure 2, is a side elevation;

Figure 3, is a section on line 3—3 of Figure 2;

Figure 4 is a section on line 4—4 of Figure 3, and

Figure 5, is a section on line 5—5 of Figure 1.

The two back sections 1 and 2 are rigidly secured to hollow cheek pieces 3 and 4, to which latter the side covers (not shown) 45 of the book are hinged in the usual manner. The section 2 terminates at each end in a hook-like member 5 which receives the ends of the section 1 in telescopic relation.

From the free edge of the section 1 preferably at the middle part thereof and directly opposite the cheek piece 3 to which said section is secured, extends a hook 6 that is received in an elongated slot 7 in the inner face of the section 1, and opposite this 55 slot the cheek piece 4 has a countersunk

part 8 formed in its outer face, and in the bottom of this countersunk portion is a slot 9. While this countersunk portion is shown as of a general oval shape with concavo-convex surfaces, the shape and surface 60 contour thereof is immaterial, and such portion may be formed so as to present in appearance a rectangular box-like structure, and the invention is therefore not limited in this respect.

Through this slot 9 extends the shank 65 of a finger piece 10, the inner end of such shank being secured to a latch bar 11 which bears snugly against the bottom of the countersunk part 8 and is confined and guided as to its lengthwise movements within a suitable opening in the inner face of said cheek piece 4.

Through this slot 9 extends the shank 70 of a finger piece 10, the inner end of such shank being secured to a latch bar 11 which bears snugly against the bottom of the countersunk part 8 and is confined and guided as to its lengthwise movements within a suitable opening in the inner face of said cheek piece 4.

This latch is cut away directly opposite the slot 7 so as to form comparatively long 75 and short tongues 12 and 14 respectively, and when the two sections 1 and 2 are assembled the hook 6 will extend through the opening 7 and into and beyond the space between the tongues 12 and 14, so that when 80 the latch bar 11 is operated the tongue 12 will be passed beneath the bill of the hook and thereby securely lock the sections together.

The usual sheet engaging posts 15 are 85 carried by the two sections and cheek pieces and received in apertures provided for them in the respective opposite sections and cheek pieces.

From the foregoing it will be apparent 90 that the latch is located centrally between the telescopic ends of the sections, having a holding action equally upon each of such ends. The latch is easily slid into and out of latching position, and is the sole element 95 which is movable, the latch being a unitary structure in itself.

If desired, the latch bar 11 may be provided with slits forming spring fingers 16 disposed opposite to the tongues, which 100 fingers bear against the adjacent edge of the opening in the cheek piece 4 so as to hold the latch against rattling.

What is claimed is:

1. In a metal ledger back, a pair of cheek 105 pieces having secured thereto the ledger back sections constructed at the end edges for telescoping one within the other, one of said sections having a central hook extending from its free edge while the other sec- 110

tion is provided with an elongated slot to receive said hook and is formed opposite said slot with a countersunk part, and a latch bar slidable against the inner bottom 5 face of said countersunk part and operated by means of a finger piece attached to said bar through an elongated slot in the bottom of the countersunk part, said latch having a cut away portion in one side edge whereby 10 a tongue is provided which engages beneath said hook to lock the sections together.

2. In a metal ledger back, a pair of telescopic members, one member provided with an elongated slot and a slotted countersunk 15 part opposite said slot, the other member having a hook projecting from the central portion of its free edge, a latch bar capable of sliding movements along the bottom of said countersunk part and operated by a

finger piece secured to said bar through the 20 slot in said part, whereby, when the sections are assembled with the hook of one section extending through the slot in the other, said bar may be operated to engage immediately beneath the hook and thereby lock 25 the members together.

3. In a metal ledger back, a pair of telescopic members, a hook carried by one member, a keeper carried by the other member for receiving the hook, a countersunk part 30 associated with the keeper, a slidable latch bar for the hook resiliently engaging the bottom surface of said countersunk part, and means for operating the latch bar housed within the concavity of said part.

In testimony whereof I affix my signature hereto.

JOHN SCHADE.
